VENTILATED LAMP HOUSING

Albert Liabastre, Great Neck, N. Y.

Application March 26, 1942, Serial No. 436,226

4 Claims. (Cl. 240—47)

This invention relates to lamp housings for electrical fixtures and is intended primarily for use in connection with lighting fixtures for sewing machines. Such fixtures are mounted directly on the sewing machine in such manner as to permit light to be directed upon work passing beneath the foot of the sewing machine. In order to satisfactorily carry out the function of lighting the work directly at the needle, a fairly bright electric lamp is required and this lamp must be of relatively small size so that its housing and associated reflector will not unduly encumber the machine.

Lighting fixtures of this general character are well known, but experience has shown that the lamps thereof are relatively short lived. This is due to the vibration to which such lamps are subjected and to the excessive heat which accumulates in the lamp housing. Not only does this heat shorten the life of the lamp as well as the insulation of the electric conductors which feed current to the lamp, but the lamp housing itself becomes so hot that if it is inadvertently touched by the hand of the operator a serious burn may result. Attempts heretofore made to ventilate fixtures of this type have proven wholly inadequate in the solution of the problem.

The present invention is directed to a construction whereby the disadvantages referred to are eliminated, the life of the lamp and its electrical connections are materially prolonged and the lamp housing and its associated reflector are maintained at all times at such temperature as not to constitute a hazard of burning to the operator of the machine which may be equipped with such a lamp.

Another feature of the invention is to so support the lamp housing that the parts thereof may be effectually bound together in a manner to permit the lamp housing or reflector to be grasped to allow of adjustment of the lamp without shifting the parts of the lamp housing with respect to one another or causing them to become loosened.

An important object of this invention is to provide an economical construction thoroughly efficient in its operation and absolutely trustworthy in its performance.

Generally speaking the present invention is characterized by the provision of a housing shell which is preferably metallic and with a portion of which a reflector may be made integral.

Positioned within the shell and spaced from the walls thereof by a channeled spacing member is the core of a lamp socket. The lamp is

screwed into the socket so as to occupy a position within the reflector. The spacing member is provided with a series of longitudinally extending pasages which open at their bottom to the interior of the reflector and communicate at their top with a chamber in the upper portion of the shell, while the top of the shell is provided with a number of perforations. These perforations and the passages or channels in the spacing member form, collectively, a number of ventilating flues through which the heat of the lamp is adapted to escape through the interior of the shell. It is noted in practice that, as the heat of the lamp passes through these flues, it carries with it a considerable amount of relatively cool atmospheric air which, circulating as it does through the interior of the shell, keeps the shell and the reflector fairly cool and prevents overheating of the lamp socket core or the electrical connections and insulation associated therewith.

Features of the invention, other than those adverted to, will be apparent from the hereinafter detailed description and claims, when read in conjunction with the accompanying drawing.

The accompanying drawing illustrates one practical embodiment of the invention, but the construction therein shown is to be understood as illustrative only, and not as defining the limits of the invention.

Figure 1 is a central vertical section through a housing embodying the present invention with the lamp socket core and electrical connections shown in elevation.

Figure 2 shows the structural parts of the device dismantled and in substantially cooperative positions.

Figure 3 is a plan view looking down upon the top of the housing shell.

Figure 4 is a section on the line 4—4 of Figure 1.

Figure 5 is a perspective view of the housing showing the same mounted on a fixture of the character referred to.

Figure 6 shows a fitting for supporting the lamp housing upon the bracket of the fixture, this fitting being also indicated in dotted lines in Figure 1.

In the drawing, the housing is shown as formed of two telescoping sections 1 and 2 respectively. The upper section 1 is in the form of a substantially cylindrical shell open at its bottom and having a top wall 3. Centrally of this top wall is an upwardly projecting integral cylindrical boss

4 open at both ends and about the boss the top wall 3 of the shell is provided with a series of annularly disposed openings or perforations 5. The lower shell section 2 telescopes into the upper shell section 1. It is open at both its top and bottom and formed integral with its bottom is a shade or reflector 6 of any appropriate shape. At the junction between the reflector and the shell section 2 is formed a slight constriction 7 constituting a seat for a tubular spacer 8.

The spacer 8 of insulating material is positioned in the shell sections 1 and 2. It is of a size to closely fit within the lower shell section 2 and seat at its bottom upon the constriction 7 and extend to a point adjacent the under side of the top wall 3 of the upper shell section. In the outer surface of the spacer 8 are formed a series of parallel channels or passages 9 so that in cross axial section the spacer is externally castellated, providing the passages 9 which extend uninterruptedly and unobstructedly from the interior of the reflector 6 to the perforated top wall 3 of the shell. An appropriate lamp socket core 10 is fitted into the interior of the spacer 8 which is provided intermediate its ends with a shoulder 11 on which the upper portion of the core seats, as shown best in Figure 1, with the usual brass lamp socket 12 projecting downwardly to substantially the top of the reflector, so that a lamp 13 may be screwed thereinto and occupy a position within the reflector. The shoulder 11 keeps the socket core from falling out of the bottom of the housing.

Current for energizing the lamp is fed to the core 10 through insulating conductors 14 extending to the housing through BX cable 14a with the end of the cable protruding into and preferably anchored within the tubular boss 4, as shown best in Figs. 1 and 5.

The telescoping sections 1 and 2 of the shell may be secured together in any appropriate way, but, in carrying out the present invention I secure these parts together and to their mounting on the machine by means of a fitting shown in detail in Fig. 6. This fitting is formed of two complementary sheet metal stampings 15. Both stampings are provided at their upper portions with opposed clamping jaws 16 adapted to grip the tubular boss 4 of the upper shell section 1, while the lower portions of the stampings have opposed clamping jaws 17 adapted to grip the lower shell section 2. Clamping bolts 18 draw the stampings together to secure them to the lamp housing and thus secure the two telescoping sections of the housing to one another. The stampings are moreover provided with rearwardly projecting lugs 19 provided interiorly with sockets or depressions 20 forming the female units of a ball and socket joint. The male unit of this joint is in the form of a ball 21 indicated in Figure 1 as adapted to articulate in the opposing sockets 20. This ball is rigid with the lower end of a stay link 22, the opposite end of which has a similar ball received in opposing sockets 23 in the legs of a U-shaped clamp 24 which is clamped about a tubular supporting arm 25 and in engagement with the cooperating ball on the upper end of the stay link, by a bolt 26.

The stay link 22 thus has a universal joint connection with both the tubular supporting arm 25 and the lamp housing and reflector, thereby providing for tilting adjustment of the lamp housing into the most efficient position to illuminate the work to be done. The fitting which com-

prises the stampings 15 thus serves not only to hold the sections of the housing shell together, but also serves as a universal mounting for the housing and reflector.

5 The parts of the housing are assembled after the manner indicated in Fig. 2; that is to say the spacer 8 is first lowered into the lower shell section 2 to seat upon the constriction 7. The core 10 is next introduced into the spacer 8 until it comes to a seat on the shoulder 11 and the upper shell section 1 is then passed over the upper end of the lower shell section 2 to close and complete the housing shell. It will of course be understood that the wiring connections are made before assembling the parts and it will be noted from Fig. 2 that the upper shell section 1, the lower shell section 2, and the spacer 8 are all slotted as indicated at 27 to permit the passage of the switch button 28 of the socket core. A button type of core is shown in the drawing, although a pull chain socket core may be employed if desired.

When the parts are assembled as described with a lamp screwed into the socket core and in operation, heat rising from the lamp and entraining cool air will pass upwardly through the channels or passages 9 of the spacer and out through the perforations 5 of the shell, as indicated by the arrows in Fig. 1. This circulation of air will 30 keep all parts of the structure sufficiently cool to preclude overheating and thus eliminate or minimize the disadvantages which would be present in the absence of this ventilation.

Experience has shown that the parts keep unusually cool in the structure of my invention. The life of the lamp is materially increased and the melting away of lamp contacts, so common in conventional constructions, is unknown with the structure of the present invention. The insulation of the electrical connections 14 is not unduly heated and an operator may safely grasp the exterior of the housing with a bare hand to move the lamp into the desired adjustment without fear of burning. The parts entering into the structure may be economically manufactured and expeditiously assembled and with the type of mounting fitting which I have described close tolerances between the parts are unnecessary.

The foregoing detailed description sets forth the invention in its preferred practical form, but the invention is to be understood as fully commensurate with the appended claims.

Having thus fully described the invention, what I claim as new and desire to secure by Letters 55 Patent is:

1. A lamp housing comprising a shell open at its bottom and having in its top wall a series of ventilating openings; an insulated spacer fitted into the shell and extending for substantially the full length thereof, said insulating spacer being provided with longitudinal passages extending for the full length of the spacer to provide in conjunction with the aligned openings in the top of the shell a plurality of unobstructed straight-through flues extending longitudinally through the shell, a lamp socket core fitted into the interior of the spacer and provided therein at its lower end with a socket to receive a threaded base of an incandescent lamp, and a lamp shade carried by the lower end of the shell, whereby heat may escape from the interior of the shade in an entirely upward direction by way of said straight-through flues and out of the top of the shell.

2. A lamp housing comprising upper and lower telescoping shell sections having a sliding fit be-

tween them, the upper of which is provided in its top with ventilating openings and in its side wall with an aperture for the passage of a switch operating member, the lower shell section having a registering aperture in its side wall for the passage of the switch operating member and said side wall being otherwise sealed, a lamp shade at the lower end of the lower shell section, an internal constriction also at the lower end of the lower shell section, a tubular spacer within the lower shell section and seated at its lower end upon said constriction and provided with unobstructed longitudinal passages forming with the ventilating openings in the upper shell section unobstructed straight-through flues for the escape of heated air from the shade through the lamp housing, a lamp socket core positioned within and embraced by the spacer with its switch operating member extending through the registering apertures in the side walls of both shell sections, wiring connections passing through and insulated from the upper shell section and secured to the terminals of the socket core, and means for securing said shell sections in telescoping relation.

3. A lamp housing comprising upper and lower telescoping shell sections having a sliding fit between them, the upper of which is provided in its top with ventilating openings and the lower of which has an aperture in its side wall for the passage of the switch operating member and said side wall being otherwise sealed, a lamp shade at the lower end of the lower shell section, an internal constriction also at the lower end of said lower shell section, a tubular spacer within the lower shell section and seated at its lower end upon said constriction and provided with unobstructed longitudinal passages forming with the ventilating openings in the upper shell section unobstructed straight-through flues for the escape of heated air from the shade through the lamp housing, a lamp socket core positioned within and embraced by the spacer with its switch operating member extending through the aperture in the side wall of the lower shell section, wiring connections passing through and insulated from the lower shell section and secured to the terminals

of the socket core, and means for securing said shell sections in telescoping relation.

4. A lamp housing comprising upper and lower telescoping shell sections having a sliding fit between them, the upper of which is provided in its top with ventilating openings and in its side wall with an aperture for the passage of a switch operating member, the lower shell section having a registering aperture in its side wall for the passage of the switch operating member and said side wall being otherwise sealed, a lamp shade at the lower end of the lower shell section, an internal constriction also at the lower end of the lower shell section, a tubular spacer within the lower shell section and seated at its lower end upon said constriction and provided with unobstructed longitudinal passages forming with the ventilating openings in the upper shell section unobstructed straight-through flues for the escape of heated air from the shade through the lamp housing, a lamp socket core positioned within and embraced by the spacer with its switch operating member extending through the registering apertures in the side walls of both shell sections, wiring connections passing through and insulated from the upper shell section and secured to the terminals of the socket core, means for securing said shell sections in telescoping relation and for supporting the housing, said means including a fitting comprising complementary stampings provided at their upper portions with a pair of opposed complementary clamping jaws adapted to grip the upper shell section and at their lower portions with an additional pair of opposed complementary clamping jaws adapted to grip the lower shell section, said stampings also having opposed interior sockets forming the female unit of a ball and socket joint, a male articulating supporting element seated in said sockets, and means for drawing the stampings toward one another to clamp both pairs of jaws of the stampings to the upper and lower shell sections and simultaneously produce the desired friction between the ball and socket units of said universal joint.
